UNITED STATES PATENT OFFICE.

THOMAS SHAW, OF PHILADELPHIA, PENNSYLVANIA.

FRICITION-BUFFER.

SPECIFICATION forming part of Letters Patent No. 267,727, dated November 21, 1882.

Application filed August 24, 1882. (No model.)

To all whom it may concern:

Be it known that I, THOMAS SHAW, of the city and county of Philadelphia, Pennsylvania, have invented a new and Improved Friction-
5 Brake Buffer for Arresting Motion of Cars, Engines, &c.; and I hereby declare the following to be a full, clear, and exact description of the same, reference being had to the accompanying drawings, and to the letters of reference marked thereon.

My invention consists in providing a sliding brake-shoe upon any suitable rails in line of the track, arranged as hereinafter described.

The object of the invention is to absorb the 15 force of moving trains at railroad terminals to prevent destruction to cars and other property.

In order to enable others to use and practice my invention, I will proceed to describe its construction and operation.

20 On reference to the accompanying drawings, which form part of this specification, Figure 1 represents a longitudinal vertical section through center of the shoe and upon the rail; and Fig. 2 represents an end view in direction 25 of arrow *a*, with part of front removed to show end view of spring *f*.

Similar letters refer to similar parts.

a is an ordinary T-rail, on which a cast-iron or metal shoe, *e*, is caused to slide. The bottom 30 part of the shoe *b* is of the configuration shown at Fig. 2, to cause it to fit close to and clasp the under side of the rail. A metal friction-plate, *h*, is placed upon the top of the rail *a*, and strong springs *f* are placed above and 35 caused to press upon friction-plate *h* by screws *d*. Said springs *f* are provided with projecting rivet-heads that enter center of bolts *d* and keep said springs in their place. The shoe is cast with the space shown in Fig. 2 to 40 permit the entrance of the rail *a* and the springs *f* and the friction-plate *h*. The end *g* is cast open for the insertion of springs *f*, and closed by metal plate *g*, bolted in place by ordinary bolts. The bolts *d* are made of such 45 length as will give any predetermined pressure upon the said springs *f*, to cause any predetermined load upon the friction-plate *h*, with its corresponding friction upon the under side of said rail *a*, all for the purpose hereinafter 50 described. The front or shield part, *c*, is arranged to receive the front center part of the

cow-catcher of a locomotive, in which event the rail *a* is secured in the center of the track. When this same shoe is used to catch upon the wheels of the cars a separate casting (of concave configuration adapted to the shape of the wheel) is bolted to the shield *c*, all to operate as hereinafter described. 55

The shoe is operated in this wise: After being secured to the rail in the manner afore described, the springs are pressed down by screws *d* by turning said screws by ordinary wrench until any predetermined pressure of one or more tons is exerted upon the same, according to the desire of the operator, when the shoe 60 will slide upon the rail whenever said force is overcome by an engine or car wheel pressing upon the shield *c*, overcomes the induced frictional resistance, and while sliding opposes the moving force with its full predetermined 65 power until the momentum is overcome, causing the motion to be arrested in a gradual and cushion-like manner without destructive effect, after which the shoe has its friction reduced to the minimum by unscrewing the 70 screws *d* and taking the load off the springs, when the shoe is replaced in its former position, ready to be operated as afore described. When the shoe is arranged for the cow-catcher 75 of a locomotive the rail on which the shoe 80 clasps is placed in the center of the ordinary track and firmly bolted and spiked to the sleepers.

When used for contact with car-wheels a shoe of the configuration of the wheel, as before 85 described, is bolted to the shield *c*, in which event two shoes are used, one on each track, and both set by spring-pressure, as afore described. The wheels of any moving car striking the shoes causes the shoes to slide as 90 soon as the frictional resistance is overcome, opposed by the friction until the momentum of the car be overcome. A moving train that would strike a one-hundred-ton blow on an ordinary bumper would be reduced to one and a 95 half-ton resistance on this shoe for ten feet of stroke, or three-quarter ton resistance for twenty-feet stroke, which would be without any destructive effect, while the one-hundred-ton blow would break the bumper and the 100 platform of the cars, showing the advantage of this method of inducing frictional resistance.

outside and separate from the car, engine, or train.

It will be observed that these shoes can be variously fashioned to produce the same result without having it the exact configuration shown, and that the same result can be brought about by holding the shoe stationary and moving the rail, using the rail as a ram of resistance—sliding when resisted, &c. I therefore do not wish to confine myself to the exact configuration shown.

What I claim, and desire to secure by Letters Patent, is—

The combination, with a rail or equivalent device, of a friction-brake shoe located outside and separate from the car, said shoe being adapted to slide upon the rail, resisting the movement of a car or engine, substantially as and for the purpose set forth.

THOMAS SHAW.
